WINDOW VENTILATOR

Fred M. Robinson, Chicago, Ill., assignor to Mary
Robinson, Chicago, Ill.

Application August 17, 1936, Serial No. 96,381

15 Claims. (Cl. 98—99)

This invention relates to window ventilators, and aims to provide a ventilator that will permit maximum circulation of air through a window opening while effectively preventing the admittance of rain or other forms of precipitation into the room, or coming in contact with those portions forming the confines of the window opening, such as the guideways of the window closure, or sash, and the sill portion therebetween at the base of the window frame.

Other objects are to provide such a ventilator that will be so mounted on the window frame as to permit its movement into and out of cooperative relation with the window opening with the least amount of effort; that will be constrained for such movement between limits; and that will be removable from the window and attachable thereto with the least amount of effort.

Other objects and advantages will become apparent by reference to the specification and the accompanying drawings, in which:

Fig. 1 is a view in elevation of the lower portion of an ordinary window as viewed from its inner side, and illustrating one embodiment of the ventilator in its position with the window closed, and with parts broken away to disclose certain parts otherwise hidden and to reduce the size of the figure.

Fig. 2 is a vertical section taken substantially on the section line 2—2 of Fig. 1, showing an end elevation of the ventilator with certain parts in section.

Fig. 3 is a perspective view of an end portion of the ventilator with certain parts in separated relation.

Fig. 4 is a vertical detail section of an end portion of the ventilator, as taken substantially on the section line 4—4 of Fig. 2.

Fig. 5 is a view in elevation of the lower portion of the window as viewed from its outer side, with the ventilator shown in position within the window opening, and with parts broken away to disclose other parts otherwise hidden and to reduce the figure.

Fig. 6 is a vertical section taken substantially on the section line 6—6 of Fig. 5.

Fig. 7 is a plan section taken on the section line 7—7 of Fig. 5.

The ventilator illustrated forms only one embodiment of the invention for application to an ordinary window. Such a window, as shown, generally comprises a frame including upright side frames, or frame members, 1 mounted on a horizontal base portion 2 including an outer window sill 3 and an inner window ledge 4. Between the

side frame members 1 is a window closure or sash 5 usually provided with a glass panel 6 and being mounted for vertical sliding movement over the sill within the opposed guideways 7 of the side frame members, respectively, so that when lowered the bottom of the sash is abutting the shoulder between the sill and the window ledge.

The ventilator of the invention comprises an air deflecting head 10 adapted to be positioned within the window opening in a raised position 10 of the sash, as seen in Fig. 6, so that it is disposed between the guideways of the sash and over the sill portion therebetween forming the confines of the opening. The air deflecting head includes upright end walls 11 connected at their top ends 15 by means of a tie element or tube 12 extending therebetween and secured thereto by bolts 12a respectively. The head also includes a front wall portion 14 extending between the lower end portions of the end walls at their front edges and 20 being in the form of a sheet metal strip suitably secured at its ends to the end walls. Thus the end walls 11, the tie element 12 and the front wall portion comprise an open rectangular framework for the head.

Mounted on the end walls so as extend therebetween, is a series of vertically spaced air deflecting members or louvers 15, in the form of glass partitions inclined in such a manner as to form inwardly and upwardly inclined air passages continuing through the window opening from the plane of the outer face of the sash. The upper edge portions of the partitions are arranged to extend considerably inward of the window opening, and with the lower edge of one disposed 30 considerably below the horizontal plane of the upper edge of its adjacent partition, so as to co-operate in effectively preventing rain from entering the room under violent wind conditions. The front wall portion 14 is arranged to form a downward continuation of the lower partition to prevent rain from entering the sill portion between the guideways of the window, wherein said wall portion has an upper flange portion 16 continuing under the lower end or edge of said partition.

Each end wall 11 is formed with an outer plate 18 and an inner plate 19 suitably secured together in spaced relation, with the inner plate having inclined grooves 20 within which the ends 50 of the partitions 15 are received. Each end wall has a front edge portion 21 comprising a flange of an angle piece 22 secured to the outer plate 18 of the wall with the ends of the grooves at the edge closed by the flange. Each end wall has a 55

rear edge portion 23 comprising a flange of an angle piece 24 removably secured to the outer plate 18 of the wall by screws 25 with the rear ends of the grooves 20 being closed by the flange, 5 so that the partitions may be replaced if damaged.

To prevent rain from entering the guideways 7 of the window sash, each end wall 11 has a lateral flange 26 extending from its front edge portion 10 and arranged to contact with an upright sealing strip in the form of a bar 27 secured on the parting strip 28 of the window frame between each guideway and a similar guideway 29 in the side frame portions 1 for the upper window sash, (not 15 shown). Thus the flanges 26 provide rain protecting guards for the guideways 7, and also form an effective seal with the upright bars 27.

To further prevent fine snow from entering the passageways between the partitions 15 of the air 20 deflecting head under severe wind conditions, a screen 30 is provided for the head, and is arranged to extend across the front thereof so as to cover the window opening. The screen includes a rectangular frame 31 within which the 25 screen is mounted, with the frame being slidably received in opposed guideways 32 in the front edge portions of the end walls 11 of the head.

The air deflecting head is mounted on the window frame to be movable back and forth between limits, as from its position within the confines of the window opening to a position over 30 the window ledge, so as to be out of the path of the window sash when same is closed. To this end, two supports 35 are provided in the form of 35 upright metal strips having apertures 36 to be fixedly mounted, by screws or the like, on the side frame portions 1, respectively, and being arranged above the window ledge. On each support is removably mounted a similar bracket 37 40 in the form of an upright bar on which are pivotally mounted two parallel links 38 in turn pivotally connected on an adjacent end wall 11 of the head. The supports, brackets and links are so arranged, that when the head is in the window 45 opening, as seen in Fig. 6, the links extend from the brackets slightly inclined upward from the horizontal toward the window opening, so as to urge the flanges 26 of the head into sealing engagement with the upright bars 27 on the parting 50 strips, as the front wall portion 14 rests upon the window sill, and whereby the head may be moved from the window opening into a raised position over the window ledge, as seen in Fig. 2. The head is limited for movement into raised 55 position by the pivot pins 39 pivotally connecting the links with the end wall having enlarged heads which engage the brackets, and whereby the links on each end wall are prevented from assuming a dead center relationship with respect 60 to each other. For convenience in raising the head, each end wall 11 is provided with a suitable handle 40 mounted on its rear edge portion 23. To counterbalance the weight of the head when same is raised, a tension spring 41 is provided at each end wall with one end connected to its adjacent bracket and its other end connected with the end wall.

To hold the air deflecting head in raised position over the window ledge, as well as to prevent 70 movement of the brackets with respect thereto when removed from the supports 35, releasable holding means is provided and includes a holding dog 42 pivotally mounted on each end wall, as at 43, with a notch 44 in its under side within which 75 is received a lateral pin 45 of its adjacent bracket,

and with the free end of the dog arranged closely to the handle of the wall to render same accessible when it is desired to lower the head, as best seen in Fig. 2. The holding dog 42 is resiliently held in engagement with the pin 45 of its bracket 5 by a coiled tension spring 46 interconnected between the dog and the end wall. Each holding dog is arranged to slide on its respective pin 45 as the head is lowered, and has a hook portion 46a at its end for hooking engagement with the 10 pin to prevent any great amount of movement of the head with respect to the brackets beyond its normal range of movement while attached to the window frame. On each end wall 11 is mounted a spring pressed detent or pawl 47 for engaging 15 its holding dog to hold same in engagement with its respective pin 45, when the head is in raised position, so as to necessitate releasing the pawl before the dog is rendered releasable in preventing accidental release of the dogs. 20

The brackets 37 are removably mounted on the supports 35, respectively, by each support having laterally extending mounting pins 48 and 49 arranged at its top and bottom ends respectively, with the lower pin 49 adapted to be received in 25 a slot 50 in the lower end of its adjacent bracket so as to form a pivotal connection, and with its top pin 48 adapted to engage within a notch 51 in one side of the bracket when the brackets are rotated upon the pins 49 into upright position 30 alongside the supports.

For locking the brackets in position on the supports, the brackets are provided with a releasable lock device 52 at their upper ends for holding the upper pins 48 of the supports in the notches 51 35 of the brackets, as best seen in Fig. 2. Each locking device includes a spring pressed detent or locking bolt 52a slidably mounted in a lock housing portion 53 on the upper end of each bracket, with one end of the bolt normally closing 40 the notch 51 of the bracket, so as to confine the pin 48 of its adjacent support therein. In the lock housing is a coiled spring 54 urging the bolt into locking position, with the bolt having a lateral handle or pin 55 extending through a slot 56 45 in the wall of the housing for releasing the bolt and for limiting its movement. The upper active end of the bolt is tapered as at 57 for cooperative engagement with the pin 48 in causing same to snap into locking position when the brackets 50 are assembled with the supports.

To prevent removal of the brackets from the supports when the air deflecting head is disposed in its lowered position within the window opening, for the reason that the lower portion of the 55 flanges 26 below the horizontal plane of the pins 49 of the supports would otherwise jam against the sealing bars 27 on the parting strips as the brackets are rotated on the pins away from the window, as well as to prevent unauthorized removal of the ventilator from the outer side of the window, means is provided to render the locking device of each bracket releasable only when the head is moved into a raised position. To accomplish this, the outer plates 18 of the 60 end walls 11 each have an upper portion 58 formed with an arcuate edge portion 59 arranged to be in the path of movement of the handle 55 of its adjacent locking bolt 52a, so as to prevent its retraction, while the air deflecting head is in 70 lowered position and until the head is raised to a position approaching its uppermost limit, whereupon on continued upward movement of the head said edge portion 59 is brought out of the path of the handle of the bolt in rendering 75

same releasable, as best seen in Figs. 2, 5 and 6.

By virtue of the structure described, a ventilator has been provided that will permit considerable circulation of air through the window opening without those portions of the window frame important to the proper functioning of the lower window sash, such as the guideways and the sill portion upon which the sash is adapted to rest, being subjected to deterioration by contact with rain or snow, as such window frames are usually constructed of wood. Further, by reason of the manner in which the air deflecting head is mounted for movement between limits, wherein it is constrained for movement to definite positions with respect to the window opening, its adjustment is easily accomplished, and by virtue of the manner in which the head is removably mounted on the window frame, its attachment thereto may be effected with little effort.

Another important advantage of the invention is that, when the air deflecting head is in position within the window opening with the front edges of its end-walls in sealed connection with the parting-strips of the window frame, rain or snow is prevented from coming in contact with the links, springs, holding apparatus and other mechanism disposed at the side of each end-wall. Thus corrosion of said mechanism is greatly prevented, and the proper operation of the ventilator assured.

Having thus described my invention, I claim:

1. In a window ventilator, the combination of a support adapted to be fixedly mounted upon a window frame, a bracket removably mounted on the support, an air deflecting head mounted for limited movement on the bracket so that same may be moved into and out of cooperative relation with the window opening, and including releasable locking means for locking the bracket in position on the support.

2. In a window ventilator, the combination of a support adapted to be fixedly mounted upon a window frame, a bracket removably mounted on the support, an air deflecting head mounted for limited movement on the bracket so that same may be moved into and out of cooperative relation with the window opening, and including releasable locking means for locking the bracket in position on the support and arranged to be rendered releasable upon movement of the air deflecting head out of cooperative relation with the window opening.

3. In a window ventilator, the combination of a support adapted to be fixedly mounted upon a window frame, a bracket removably mounted on the support, an air deflecting head mounted for limited movement on the bracket so that same may be moved into and out of cooperative relation with the window opening, and including releasable holding means for holding the air deflecting head at one limit of its said movement on the bracket.

4. In a window ventilator, the combination of a support adapted to be fixedly mounted upon a window frame, a bracket removably mounted on the support, an air deflecting head mounted for limited movement on the bracket so that same may be moved into and out of cooperative relation with the window opening, and including releasable holding means for holding the air deflecting head at its limit of movement out of cooperative relation with the window opening.

5. In a window ventilator, the combination of a support adapted to be fixedly mounted upon

a window frame, a bracket removably mounted on the support, an air deflecting head mounted for limited movement on the bracket so that same may be moved into and out of cooperative relation with the window opening, and including 5 releasable locking means for locking the bracket in position on the support and arranged to be rendered releasable upon movement of the air deflecting head out of cooperative relation with the window opening, and releasable holding 10 means for holding the air deflecting head on the bracket in its position out of cooperative relation with the opening so as to prevent movement of the bracket on the head when removed from the support. 15

6. In a window ventilator, the combination of two supports adapted to be fixedly mounted respectively on the side frame members of a window frame, a bracket removably mounted on each support, an air deflecting head arranged between 20 the brackets, linkage pivotally connected with the head and each bracket and arranged so that the head is movable from a lowered position in cooperative relation with the window opening to a raised position out of cooperative relation with 25 the opening and over the window ledge, and including releasable locking means cooperating between each bracket and its support to lock the bracket in position on the support. 29

7. In a window ventilator, the combination of 30

two supports adapted to be fixedly mounted respectively on the side frame members of a window frame, a bracket removably mounted on each support, an air deflecting head arranged between 35 the brackets, linkage pivotally connected with the head and each bracket and arranged so that the head is movable from a lowered position in cooperative relation with the window opening to a raised position out of cooperative relation with 40 the opening and over the window ledge, including releasable locking means cooperating between each bracket and its support to lock the bracket in position on the support and with 45 means cooperating with the air deflecting head to render same releasable upon movement of the head to raised position, and releasable holding means cooperating between the head and each bracket to hold the head in raised position with respect to the brackets so as to prevent movement of the brackets on the head when removed 50 from the supports. 50

8. In a window ventilator, the combination of two supports adapted to be fixedly mounted respectively on the side frame members of a window frame, a bracket removably mounted on each support, an air deflecting head arranged between 55 the brackets, linkage pivotally connected with the head and each bracket and arranged so that the head is movable from a lowered position in cooperative relation with the window opening to a raised position out of cooperative relation with 60 the opening and over the window ledge, including releasable locking means cooperating between each bracket and its support to lock the bracket in position on the support and arranged with 65

means cooperating with the air deflecting head to render same releasable upon movement of the head to raised position, wherein the locking means includes a movable locking detent on each bracket and the head having a formation for cooperative engagement with the detent of each bracket to prevent its movement when the head is in lowered position. 70

9. In a window ventilator, the combination of 75 a movable air deflecting head adapted to be po-

sitioned within a window opening and having end-walls each of which has a straight front edge provided with a lateral flange, a sealing strip adapted to be mounted on each parting strip between the guideways in the side-frame members of the window frame and arranged to be engaged by a flange of an end-wall, and means for mounting the head on the window frame for movement into and out of position within the window opening inclusive of means operable when the head is positioned in the opening to cause the flanges to have pressure engagement with the sealing strips.

10. The structure as defined in claim 9, where-
15 in the last means comprises linkage in cooperative pivotal connection with the head and window frame and arranged so that the flanges are urged into engagement with the sealing strips by force of gravity acting upon the head.

20. 11. In a window ventilator, the combination of a movable air deflecting head adapted to be positioned within a window opening and having end-walls each of which has a straight front edge provided with a lateral flange, a sealing strip adapted to extend along and be mounted on each parting strip between the guideways in the side-frame members of the window frame and arranged to be engaged by a flange of an end-wall, and means for mounting the head for movement into and out of position within the window opening inclusive of means constraining the flanges to assume a parallel relation with the sealing strips at least as the head is moved into position with the window opening.

12. The structure as defined in claim 11, where-
in the last means comprises a pair of parallel links in cooperative pivotal connection with each end-wall and its adjacent side-frame member and arranged to remain in parallelism during 5 movement of the head.

13. In a window ventilator, an air deflecting head adapted to be positioned within a window opening and having end-walls adapted to be spaced from the side-frame members of the window frame, linkage disposed between each end-wall and its adjacent side-frame member being in cooperative pivotal connection therewith and arranged so that the head is movable from its position within the opening to a position over 10 the window ledge and out of the path of the lower window sash, and each end-wall having a lateral flange at its front edge adapted to extend in close relation to its adjacent side-frame member to provide a rain-protecting guard for the 20 linkage.

14. The structure as defined in claim 13, in-
cluding means for providing a seal between each flange and its adjacent side frame member.

15. The structure as defined in claim 13, in-
cluding two sealing strips adapted to be mounted respectively on the side-frame members and ar-
ranged so as to be engaged by the flanges when the head is positioned within the window 30 opening.

FRED M. ROBINSON.
